UNITED STATES PATENT OFFICE.

PEARL TRUMBO JONES, OF SACRAMENTO, CALIFORNIA.

COMBINED CHAIR AND IRONING BOARD.

Application filed May 23, 1922. Serial No. 563,061.

To all whom it may concern:

Be it known that I, PEARL TRUMBO JONES, a citizen of the United States, residing at Sacramento, county of Sacramento and State of California, have invented new and useful Improvements in Combined Chairs and Ironing Boards, of which the following is a specification.

This invention relates to an article of furniture and particularly pertains to a combined ironing board and chair. It is the object of the present invention to provide a new and useful article of furniture which may be optionally arranged for use as an ironing board or as a chair, the device being simple in construction and operation and sightly in appearance.

The invention contemplates the use of a frame structure embodying a chair seat, a back, and an ironing board which is so connected to the frame structure that it may be ordinarily maintained in an inconspicuous position or arranged and supported over the frame in an operating position.

One form which the invention may assume is exemplified in the following description and illustrated by way of example in the accompanying drawings, in which:

Fig. 1 is a perspective view of a structure embodying the invention and disclosing the device arranged for use as a chair.

Fig. 2 is a rear elevation of the same.

Fig. 3 is a perspective view disclosing the device arranged for use as an ironing board.

Fig. 4 is a vertical section taken on line 4-4 of Fig. 2.

Fig. 5 is a fragmentary view showing certain details of the mechanism by which the ironing board is connected to the frame.

Referring more particularly to the drawings, A generally indicates a frame structure similar in form and proportion to the frame of a chair. This frame is provided with front legs 10 and rear legs 11. The rear legs extend upwardly as shown in Fig. 1 to provide uprights for a chair back. The legs are rigidly connected to each other by a seat frame 12 and side and rear panels 13.

Mounted on the seat frame is a seat member 14 which is connected to the seat frame at the front thereof by means of hinges 15 as shown in Fig. 4. Positioned between the upwardly extending portions of the rear

legs 11 is a back member 16, this member is connected to the frame by a hinge structure 17. This hinge is clearly shown in Fig. 2 and consists of a hinge rod 18 secured at its ends in brackets 19 fastened to the legs 11 and a flat hinge bar secured to the back member. This bar is provided with lugs 20 which are turnable on the rod 18.

Connected to both the frame and the back member 16 is an ironing board 21. This board is provided with longitudinal guide rods 22 which are spaced apart and away from the inner surface of the board as shown in Fig. 4. The rods are secured to the board adjacent the upper end thereof by flanged socket members 23. It should be stated that the rods in this instance are formed of one bar which is bent in a V-shape, the base of which is flattened and secured adjacent the lower end of the ironing board as at 24.

The board is connected to a frame through the guide rods by a connection indicated at 25 in Fig. 2. This connection consists of guide sleeves 26 which are turnably mounted on a rod 27. The latter being secured at its ends within bracket bearings 28 secured on the legs 11. The sleeves 26 are each formed with a right angle extension which sleeves are bored to receive the guide rods 22.

The ironing board is also connected to the back member 16. This connection is shown in Figs. 2 and 5 and consists of a member 29 which is secured to the back member and is formed at its ends with bearings 30 for the reception of a short rod 31. This rod is also mounted in sliding collars 32 which are mounted on the guide rods 22.

The connections between the ironing board and the frame and back member permit the board to be positioned over the frame in a horizontal position as shown in dotted lines in Fig. 2. When in this position the connection 25 serves as one support therefor and the back member through the connection 33 serves as a second support. It will be seen by referring to Fig. 4 that when the ironing board assumes the position shown in dotted lines, the back member 95 assumes an inclined position. To maintain the back member rigid in this position, a pair of brace arms 34 are provided. These 100 arms are secured to the under side of the

seat board 14 and are adapted to engage a pair of sockets 35 secured in the back member.

To eliminate chattering of the connections between the ironing board and the back and frame, springs 36 are positioned between the connections as shown in Figs. 4 and 5. It is obvious that these springs will absorb any sudden shocks the board might be subjected to when it is being brought either into or out of operating position. Also they will eliminate clicking and other annoying noise caused by engagement of the metallic parts when the board is being ironed on.

By referring to Fig. 4 it is seen that a plurality of weights 37 are mounted in the compartment beneath the seat. These weights serve to maintain the structure firmly on the floor so as to eliminate any danger of upsetting the structure when it is being used as an ironing board.

The compartment disposed beneath the seat and partially inclosed by the side and rear panels 13 is provided with a bottom 38 and a hinged door 39. The latter may also be utilized to aid in supporting the structure when the ironing board is in use as shown in Fig. 3. It is obvious that the compartment may be equipped with shelves or trays, or that it may be equipped with a metallic container and used as an ice chest. This, however, forms no important part of the present invention, and is therefore not illustrated.

In operation, the structure is assembled as shown in the drawings. When it is desired to employ the device as a chair the ironing board is positioned at the rear of the frame as shown in Figs. 1 and 2. The seat member will then be resting on the seat frame and the back member will be in a vertical position and there supported by the rod and connections 25 and the hinge mechanism 17.

If it is desired to arrange the device so that the ironing board may be used; the seat is raised and the back member brought to an inclined position so that the arms 34 on the seat will engage and catch in the sockets 35. The ironing board may then be drawn upwardly and outwardly until the springs 36 engage the guide sleeves 25. The board will then be firmly placed in a horizontal position. The door 39 is then swung open to serve as a brace as indicated in Fig. 3. The device is then ready for use.

From the foregoing it is obvious that a simple and inexpensive article of furniture has been provided, the same being slightly in appearance and easily operated, also providing an article which may be used as a chair or as an ironing board.

It is to be understood that various changes in form, proportion, arrangement and construction of the various parts employed may be made by those skilled in the art, without

departing from the spirit of the invention as claimed.

Having thus described my invention, what I claim and desire to secure by Letters Patent is:

1. A combined ironing board and chair comprising a chair frame, a seat hinged to the frame at the front thereof, a back member hinged at its bottom to the frame, an ironing board, cooperating pivotal and slideable connections between the ironing board, the top of the back member and the frame whereby the ironing board may be positioned horizontally over the frame or vertically at the rear thereof, and engaging means on the seat and back member whereby they may be connected with the seat positioned vertically and the back member disposed on an incline to co-operate with the frame and support the ironing board when it is disposed horizontally over the chair frame.

2. A combined ironing board and chair comprising a chair frame, a seat hinged to the frame at the front thereof, a back member hinged at its bottom to the frame, an ironing board, co-operating pivotal and slideable connections between the ironing board,

the top of the back member and the frame whereby the ironing board may be positioned horizontally over the frame or vertically at the rear thereof, and engaging means on the seat and back member whereby they may be connected with the seat positioned vertically and the back member disposed on an incline to co-operate with the frame and support the ironing board when it is disposed horizontally over the chair frame, and a horizontally swinging door at the front of the chair frame which may be positioned to brace the chair frame relative to its support.

3. A combined chair and ironing board comprising a chair frame including upright rear posts, a seat for the frame hinged at the front thereof, a back member disposed between said posts and hingedly connected at its lower end to the frame, an ironing board,

a pair of parallel rods disposed longitudinally thereto at a distance therefrom, said rods being fixed at their ends to the board, pivotal members fixed to said back member and to the frame and slideably engaging said rods whereby said board may be disposed horizontally above the chair frame or vertically at the rear thereof, and engaging means on the seat and back member whereby the back member may be supported in an inclined position for supporting said board when it is disposed horizontally.

4. A combined chair and ironing board comprising a chair frame including upright rear posts, a seat for the frame hinged at the front thereof, a back member disposed between said posts and hingedly connected at its lower end to the frame, an ironing board,

a pair of parallel rods disposed longitudinally thereto at a distance therefrom, said rods being fixed at their ends to the board, pivotal members fixed to said back member and to the frame and slideably engaging said rods whereby said board may be disposed horizontally above the chair frame or vertically at the rear thereof, and engaging means on the seat and back member whereby the back member may be supported in an inclined position for supporting said board when it is disposed horizontally.

5. A combined chair and ironing board comprising a chair frame including upright rear posts, a seat for the frame hinged at the front thereof, a back member disposed between said posts and hingedly connected at its lower end to the frame, an ironing board,

a pair of parallel rods disposed longitudinally thereto at a distance therefrom, said rods being fixed at their ends to the board, pivotal members fixed to said back member and to the frame and slideably engaging said rods whereby said board may be disposed horizontally above the chair frame or vertically at the rear thereof, and engaging means on the seat and back member whereby the back member may be supported in an inclined position for supporting said board when it is disposed horizontally.

6. A combined chair and ironing board comprising a chair frame including upright rear posts, a seat for the frame hinged at the front thereof, a back member disposed between said posts and hingedly connected at its lower end to the frame, an ironing board,

a pair of parallel rods disposed longitudinally thereto at a distance therefrom, said rods being fixed at their ends to the board, pivotal members fixed to said back member and to the frame and slideably engaging said rods whereby said board may be disposed horizontally above the chair frame or vertically at the rear thereof, and engaging means on the seat and back member whereby the back member may be supported in an inclined position for supporting said board when it is disposed horizontally.

7. A combined chair and ironing board comprising a chair frame including upright rear posts, a seat for the frame hinged at the front thereof, a back member disposed between said posts and hingedly connected at its lower end to the frame, an ironing board,

- tudinally thereto at a distance therefrom, said rods being fixed at their ends to the board, pivotal members fixed to said back member and to the frame and slidably engaging said rods whereby said board may be disposed horizontally above the chair frame or vertically at the rear thereof, engaging means on the seat and back member whereby the back member may be supported in an inclined position for supporting said board when it is disposed horizontally, and weights supported in a concealed position by the chair frame for steadyng the frame, and a horizontally swinging member carried by the frame for bracing the same when the ironing board is disposed horizontally.
5. A combined chair and ironing board comprising a chair frame including front and rear upright posts, a seat frame connecting said posts, a seat hinged at the front of the seat frame, a back member disposed adjacent the rear posts and hingedly connected at its lower end to the frame, an ironing board, a pair of guide rods fixed to and disposed longitudinally of the board, a pair of guide sleeves pivotally connected to the chair frame and slidably engaging the guide rods, a second pair of guide sleeves pivotally connected to the back member and slidably engaging the guide rods, sockets in the front surface of the back member and adjacent the top thereof, and arms secured to the underside of the seat adapted to 35 cooperate with said sockets, whereby said seat when raised to a vertical position will serve to support said back member in an inclined position to permit the board to be disposed in a horizontal position and thereby supported by the frame and the back member.
6. A combined chair and ironing board comprising a chair frame formed of front and rear upright posts, a seat frame connecting said posts, side and back members connected to said posts, a bottom member connected therewith to form a compartment in said frame beneath the seat frame, a hinged door for said compartment, a seat hinged at the front of the frame, a back member disposed between said rear posts and hingedly connected at its bottom to said frame, an ironing board, a pair of parallel guide rods secured at their ends to said board at a spaced distance from one surface thereof, said rods being disposed longitudinally of said board, a horizontal rod fixed at its ends to the rear posts adjacent the top thereof, a pair of guide sleeves slidably mounted on the guide rods and pivotally connected to the fixed rod, a second pair of guide sleeves slidably mounted on said guide rods, the same being pivotally connected to said back member adjacent the top thereof, whereby the board may be disposed vertically at the back of the frame or horizontally over the frame, and means whereby the seat and back member may be disposed in a position to support the board when disposed over the frame.

PEARL TRUMBO JONES.
